UNITED STATES PATENT OFFICE.

JOHN P. CASEY, OF BLOOMSBURG, PENNSYLVANIA.

ELECTRIC BRAKE FOR ELEVATORS.

SPECIFICATION forming part of Letters Patent No. 593,832, dated November 16, 1897.

Application filed August 23, 1894. Serial No. 521,088. (No model.)

To all whom it may concern:

Be it known that I, JOHN P. CASEY, of the city of Bloomsburg, county of Columbia, and State of Pennsylvania, have invented an Improvement in Electric Brakes for Elevators, &c., of which the following is a specification.

My invention has reference to electric brakes for elevators, &c.; and it consists of certain improvements which are fully set forth in the following specification and shown in the accompanying drawings, which form a part thereof.

The invention forming the subject-matter of this application more particularly comprehends certain improvements in the brake-controlling devices adapted to apply the brake to the power-shaft when the motor is thrown out of operation and vice versa.

The object of my improvements is to provide an electrically-operated brake which shall positively apply or remove the braking friction and which shall be independent of any variation in the flow of current through the motor due to its variable speed. Heretofore considerable difficulty has arisen in applying the electric brake to an electrically-actuated elevator from the fact that when the brake-solenoid is in series with the motor or armature thereof the variations in the speed of the armature—such, for instance, as take place when the elevator is descending—produce a higher counter electromotive force, which checks the current flowing through the brake-solenoid to such an extent as to unintentionally apply the brake, the said brake being applied at a time when it is desirable to keep it out of action. This difficulty is always liable to happen where a single coil is employed to operate the brake and when the brake is in series with the motor-armature. The difficulty can be obviated by employing the shunt-coil as the solenoid for the brake, but this would require a very large coil to work with any economy and to make the brake quickly responsive. These defects are entirely overcome by the use of my invention, because by employing a compound winding for my brake-magnet I may have the low resistance-coil in series with the armature of the motor and the high-resistance shunt-coil

in parallel with the armature. The action of this construction is that the large current flowing through the armature causes instantaneous action on the brake-core to remove the brake, and the energy of the high-resistance shunt-coil causes the core to remain in position to keep the brake out of action when once it has been drawn into the solenoid and until the motor-circuit is broken. It will be understood that the high-resistance coil has practically nothing to do except hold the core in its raised position after the work has been accomplished by the series solenoid, whereby the current in the series solenoid or armature of the motor may vary within wide limits without permitting the brake to be accidentally applied.

My improvements are adapted, in connection with any braking device, for any class of machinery, though I have shown it especially adapted to electric elevators as illustrating an advantageous use of the said improvement.

The general construction of the apparatus will be better understood by reference to the accompanying drawings, in which—

Figure 1 is a side elevation of an electric elevator embodying my improvements. Fig. 2 is a front elevation of my improved braking device with the power-shaft in section, and Fig. 3 is a transverse section through the friction-brake pulley and band.

A is the winding-drum adapted to take up and pay out the cable B, which leads to the cage or any movable device. The said drum A is rotated by means of worm and worm-wheel gearing C, the latter being operated through the power-shaft c and the electric motor D. A switch-lever N and contacts 1, 2, 3, 4, 5, and 6 control the current from the main conductors O, branch conductors P R, armature-circuit T, and field-magnet circuit S, whereby the motor may be caused to be put into and out of operation and reversed as to its direction of rotation. The positive conductor of the line-circuits O is connected by branch circuit P with the two contacts 3 3. The negative-line conductor is connected by the branch circuits R R with the two contacts 5 5. The terminals of the field-magnets of the motor are respectively con-

nected with the contacts 4 4 6 6. The terminals of the armature-circuits T are connected to the contacts 1 and 2 of the switch N. When the switch is thrown in connection with one set of terminals 3 4 5 6, the motor D rotates in one direction. When the said switch is thrown in connection with the other set of terminals 3 4 5 6, the motor runs in the reverse direction. In one of these cases the 10 drum A winds up the cable and in the other case it pays out said cable.

It is to be understood that the controlling-switch may be made in any suitable manner, the illustration herein given being simply an 15 example without reference to the details.

E is a brake-pulley secured to the power-shaft c. F is a brake-band encircling said pulley and connected at the bottom to the standard e. The upper ends of the band are 20 slightly separated and are connected to the short arms of toggle-levers G G, the long arms of which are connected with the vertically-moving magnetic core H. The core H works in a solenoid arranged within an iron casing 25 I, bolted to the frame of the machine. The top of said casing I should be of iron to increase the magnetic field necessary to raise the core H. The core H is made sufficiently heavy, so that when it is allowed to fall it will 30 apply the brake-band F to the brake-pulley. This core therefore performs not only the function of operating the toggles to remove the brake, but also constitutes the weight adapted to apply the brake. The solenoid is 35 compound wound and consists of a high-resistance coil J and a low-resistance coil K. The low-resistance coil K is in series with the armature and armature-circuit T, so that the current traversing the armature also traverses 40 the low-resistance coil K of the brake-magnet. The high-resistance coil J is in shunt relation to the armature and low-resistance coil and is supplied with current by shunt-circuit W. The construction is such that 45 when the switch N is thrown to open the motor-circuit it also opens the brake-magnet circuits and completely cuts all of the parts out of the line-circuit.

M is a dash-pot having a plunger l working 50 therein and connected by a rod L with the head of the core H, as more clearly shown in Fig. 2. This dash-pot M is adapted to cause the core H to move deliberately for the purpose of applying the brake-band gradually and thereby prevent any injury to the apparatus due to sudden stoppage.

In operation, when the switch N is thrown to close the circuit through the motor, as indicated, the current traverses the low-resistance coil K and armature simultaneously with the current passing through the high-resistance coil J in shunt-circuit. The combined action of the solenoid-coils instantly causes the core H to be raised and the brake-band F to be removed, so that the motor is free to operate the power devices of the ele-

vator. When the core H is raised, it will be brought near the iron cap of the case I, and will require but little power to hold it in said raised position. This power is readily supplied by the shunt-coil, which holds the said core in its elevated position and the brake out of action so long as the motor is in circuit, and this action takes place irrespective of the amount of current flowing through the 70 armature. The motor may run at variable speeds under this construction, generating proportionally variable counter electromotive force and changing to any extent the current flowing through the series or low-resistance 75 coils of the brake-magnet without danger of applying the friction-brake to the power-shaft.

It is evident that the mechanical or friction brake may be of any suitable construction, 85 as numerous mechanical devices for this purpose are well known, and any of them may be adapted to my improvements. The construction illustrated I have found to be excellently adapted to the purpose, however. 90

While I have shown a shunt-wound motor for operating elevator or hoisting devices, it is to be understood that a series or compound wound motor may be employed in lieu thereof.

While I prefer the construction shown, I do 95 not limit myself to the minor details thereof, as they may be modified in various ways without departing from the principles of my invention.

Having now described my invention, what 100 I claim as new, and desire to secure by Letters Patent, is—

1. The combination of a power-shaft, an electric motor to rotate said shaft, a friction gravity-brake adapted to arrest the rotation 105 of said shaft, an electromagnetic device for removing the said brake provided with high and low resistance coils for producing the same polarities in the electromagnetic devices, an electric circuit including the low-resistance 110 coil in series with the armature, a shunt-circuit including the high-resistance coil in shunt relation with the armature of the motor, and a switch device for controlling the flow of current through said circuits for always maintaining the current flowing in both coils of the brake-magnet in the same direction at any moment of time.

2. The combination of a power-shaft, a mechanical brake therefor, a vertically-movable 120 magnetic core to apply the brake by the weight of said core, a casing for said core, a compound winding arranged on said casing and composing high and low resistance coils adapted to produce similar polarities at all 125 times, current translating or consuming devices in series with the low-resistance coil, and switch devices for controlling the current to said coils so that it flows through them always in the same direction at any moment 130 of time, whereby the current flowing through the low-resistance coil may raise the core of

the brake to remove the brake, and the current flowing through the high-resistance coil may assist in maintaining the brake in its elevated position irrespective of variations in
5 the current flowing through the low-resistance coil due to any action of the translating or current-consuming devices.

In testimony of which invention I have hereunto set my hand.

JOHN P. CASEY.
